New York, N. Y., a corporation of Delaware

Application September 13, 1944, Serial No. 115,289

Term of patent 14 years

(Cl. D58—12)

To all whom it may concern:

Be it known that we, William F. Wise, a citizen of the United States, residing at Detroit, in the county of Wayne and State of Michigan, and Leonard A. Fannon, a citizen of the United States residing at Detroit, in the county of Wayne and State of Michigan, have invented a new, original, and ornamental Design for a Container Bottom, of which the following is a specification, reference being had to the accompanying drawings, forming a part thereof, wherein

Figure 1 is a perspective view of a container bottom showing our new design;

Figure 2 is a top plan view;

Figure 3 is an edge view; and

Figure 4 is a bottom plan view thereof.

The dotted line illustration of the side walls of the container of Figure 1 is for illustrative purposes only.

We claim:

The ornamental design for a container bottom, substantially as shown and described.

WILLIAM F. WISE.
LEONARD A. FANNON.
